UNITED STATES PATENT OFFICE.

HUGH L. SHELLABARGER, OF CASTLE ROCK, COLORADO.

FLOOR STAND FOR SUPPORTING VINEGAR BARRELS AND BARRELS OF OTHER LIQUID CONTENT.

Application filed September 7, 1926. Serial No. 133,978.

My invention relates to a new and novel floor stand for supporting vinegar barrels and barrels of other liquid content, which is dispensed at stores in retail orders.

5 And the objects of my invention are:

First: to provide a floor stand for liquid holding barrels, that is adapted to support such barrels high enough above the floor to allow its contents to be easily drawn off 10 through a spigot, placed in its bottom edge, into measures placed on the floor beneath said spigot and which tilts the barrel forwardly far enough to permit all of the liquid therein to be drawn out.

15 Second: to provide a barrel supporting floor stand, that is arranged to fit over one end of a barrel and that is provided preferably with three legs, two of which are of rocker form to allow heavy barrels of liquid content, 20 to be righted to a vertical position by an attendant, and supported on said stand, such operation without the improved stand requiring the effort of two or more persons.

Third: to provide a simple and inexpensive 25 floor stand in the form of an angle bar ring, which is adapted to be placed over one end of a barrel, and which is provided with preferably three supporting legs, two of which are in the form of rockers, whereby a heavy barrel 30 of liquid content can be easily canted from a horizontal to a vertical position by a single attendant, and supported at a distance above the floor to permit the placing of measuring vessels beneath the spigot of said barrel, 35 which is usually inserted near the lower end thereof.

I attain these objects by the mechanism illustrated in the accompanying drawings, in which:

40 Figure 1, is a side view showing a barrel supported on the improved stand in a position for use.

Figure 2, is a side view illustrating the manner in which a barrel can be canted from 45 a horizontal to a vertical position through the medium of the improved supporting stand.

Figure 3, is a plan view of the stand.

Figure 4, is a slightly enlarged sectional view on the line 4—4 of Figure 3, and

50 Figure 5, is a view of a portion of the stand showing the manner of securing the front leg thereto.

In the retail trade, certain liquid commodities, for example, vinegar, is dispensed directly from a barrel, which is supported in a ver-

tical position upon any suitable object, such as a box or piece of timber, so that the lower end portion of the barrel, in which a spigot is inserted, will be far enough above the floor to permit of measuring tins being placed beneath the said spigot. Such barrels are very heavy and require the service of two or more persons in order to place them on the required support. The present invention, however, is designed to eliminate much of the effort ordinarily required in placing such barrels upon supports, by providing an improved support, which also functions as a means of facilitating the canting of a barrel from a horizontal to a vertical position, as will hereinafter appear. Referring to the accompanying drawings:

The numeral 1 indicates a ring which is formed from an angle bar, so as to comprise an inwardly projecting circular base 75 or horizontal flange 2, and an upright rim 3 which is of a diameter corresponding to that of the end of the barrel upon which it is to be placed. To the base flange are bolted three legs which are substantially equidistant, one of the legs 4, being the front leg and the other legs 5, being rear legs. The front leg 4 is preferably about a half inch shorter than the rear legs, and is about an inch and a quarter thick, and its upper end is formed with lateral projections 6 which are bolted to the base flange 2 of the ring. The rear legs 5 are of sector shape to provide rockers, their rear edges being curved from their upper ends to the lower end portions which 80 rest upon the floor. These rockers are secured to the base flange of the ring by screws 7, which extend through the said base flange and into threaded holes in the upper edges 85 of the rockers. The rockers are preferably arranged to converge slightly, with respect to each other and their upper ends extend rearward far enough beyond the points where they are bolted to the ring, to be in line with rearmost point of the ring, as will 90 be understood by reference to Fig. 3. By converging the legs 5 the maximum mechanical strength is obtained since, as will be apparent from Fig. 3, the rocker legs 5 may be secured to a relatively narrow flange 2 at comparatively widely spaced points. The converging of the legs facilitates the handling 100 of heavy barrels since the weight of a barrel when in horizontal or in inclined position is supported at points which are closer to the 105

ly from a barrel, which is supported in a ver-

medial plane between legs 5 than would be the case if the legs were parallel. For these reasons I prefer to locate the legs 5 in planes which are approximately tangential to the 5 base flange.

In practice, where it is desired to support a barrel of any liquid content upon the improved floor stand, ring 1 is placed over one end of the barrel, and if it is necessary in order to 10 hold the ring in place, which, however, very seldom happens, a looped wire 7^A is passed under the ring just back of the front leg 4, and is hooked over a nail or screw 8, which is temporarily inserted in the lower portion of 15 the barrel above the said front leg, as clearly shown in Fig. 2. The barrel, which is now in a horizontal position, can be easily canted to a vertical position by swinging the same over upon the rockers 5 until it rests squarely 20 upon the rockers and upon the front leg 4, and as the front leg is slightly shorter than the rear legs or rockers, the barrel will have a slightly forward inclination, as clearly shown in Fig. 1. A spigot 9, is inserted in a hole in 25 the lower end portion of the barrel a slight distance from the bottom head thereof, while the barrel is still in a horizontal position, and as the legs of the barrel are about twelve inches long, this spigot will be high enough 30 above the floor to permit of measuring vessels being placed beneath the said spigot to be filled therefrom. As the barrel has a slightly forward inclination, and the spigot is located near the bottom head of the barrel. 35 practically all of the contents of the barrel

can thus be drawn off through the spigot. The wire 7^A is only a temporary expedient to hold the ring on the barrel, while the barrel is being canted from a horizontal to a vertical position and therefore, the said wire 40 serves no purpose after the barrel assumes an upright position on the base flange 2, of the stand, and may be removed. The improved stand not only provides a simple and practical manner of supporting a barrel of any 45 liquid content in position to permit the content to be drawn off as required, but it also greatly reduces the manual effort necessary in the usual manner of placing such barrels upon a support. 50

Having described my invention, what I claim as new and desire to secure by Letters Patent, is:—

A stand for supporting a barrel in vertical position, said stand comprising a ring having 55 a narrow annular supporting flange and an upwardly extending vertical flange at the outer periphery of said annular flange, and three legs secured to said ring at substantially equidistant points about the circumference 60 thereof, two of said legs being each of similar sector shape with an outer edge which curves outwardly from the base of the leg, whereby the said sector shaped legs serve as rockers for canting a barrel from horizontal 65 position into vertical position upon said stand.

In testimony whereof, I affix my signature.

HUGH L. SHELLABARGER.
